UNITED STATES PATENT OFFICE.

RALPH C. SIMMONS, OF BEVERLY, MASSACHUSETTS, ASSIGNOR TO UNITED SHOE MACHINERY CORPORATION, OF PATERSON, NEW JERSEY, A CORPORATION OF NEW JERSEY.

BLANK-SORTING MACHINE.

Application filed December 27, 1921. Serial No. 525,054.

To all whom it may concern:

Be it known that I, RALPH C. SIMMONS, a citizen of the United States, residing at Beverly, in the county of Essex and State of Massachusetts, have invented certain Improvements in Blank-Sorting Machines, of which the following description, in connection with the accompanying drawings, is a specification, like reference characters on the drawings indicating like parts in the several figures.

This invention relates to machines for sorting blanks in accordance with a selected characteristic of the blanks.

15 The invention is disclosed for the purposes of illustration in a machine for grading heel lifts. It will be understood, however, that the invention is not so limited but that the invention in its entirety and various important features thereof may have other applications and uses.

It is an object of the invention to provide a machine of the class specified which will be especially simple in construction, 25 efficient in operation, and free from the deficiencies and defects which have limited the field of usefulness of prior constructions.

In the illustrative machine and improved mechanism is provided for caliperating each 30 blank as to its thickness, and in this operation a controller is set to insure the ejection of the blank at the proper discharge station for all blanks of that thickness. As shown, the controller is also a part of the ejecting mechanism.

Conveniently, a continuously moving member serves to move the blanks to the caliperating mechanism and to eject the blanks after the caliperating operation. In a preferred construction, magazines are provided 40 above the continuously moving member, each magazine having a part arranged to co-operate with the moving member in lifting the blanks into the magazines, the blanks being distributed among the magazines in accordance with the determinations of the caliperating mechanism.

In one aspect the invention comprises two concentrically arranged conveyors one 50 of which operates to introduce the blanks into the machine while the other serves as a part of the caliperating and ejecting means by which the blanks are distributed at different stations in accordance with the determinations of the caliperating operations.

In another aspect, the invention comprises a single carrier for receiving and discharging the blanks, ejectors being provided movable with the carrier and operable to insure the discharge of the blanks at the proper stations. Conveniently, and as shown, the ejectors are parts of the means for caliperating the blanks.

In a practical form of the invention, the carrier is provided with surfaces which force the blanks into the magazines, and in the construction shown, the said surfaces appear as cam surfaces on blocks formed integrally with or attached to the upper surface of the carrier.

In addition to the features of the invention above referred to, other features consist in certain devices, combinations and arrangements of parts which will be described in the detailed specification and pointed out in the appended claims.

In the drawings:—

Figure 1 is a view in vertical section through the illustrative machine;

Fig. 2 is a detail perspective view, partly in section, of a portion of the blank caliperating and ejecting devices;

Fig. 3 is a plan view from above, partly in section, of the machine shown in Fig. 1;

Fig. 4 is a detail view partly in section of one of the ejectors together with the bottom portion of a magazine;

Fig. 5 is a perspective view of the mechanism shown in Fig. 4, illustrating the position of the parts at a different time in the cycle of operations;

Fig. 6 is a detail view in section illustrating the cooperation of the ejector and the elevator with the magazine; and

Fig. 7 is a view similar to Fig. 6 and showing the blank elevated into the magazine.

In the illustrative machine there is provided upon the standard 8 a rotary table 10 having a sleeved portion 12 to serve as a journal upon the standard. As shown, the power means for causing rotation of the table comprises a shaft 14 (Fig. 1) journaled in vertical bearings 16 and 18 on the machine frame 20, the latter being pinned as 100 at 22 to the standard 8. At the lower end of the shaft 14 is a pinion 24 arranged constantly in mesh with a second pinion 26 on the armature shaft 28 of an electric motor 105 30. At the upper end of the shaft 14 there 110

is provided a pinion or gear 32 which is in mesh with gear teeth 34 conveniently on a peripheral portion of the table 10, the construction and arrangement being such that the table is driven continuously from the motor 30 through the intermediate connections just described.

Pinned to the standard 8 at 39 above the table is a bracket 40 having a plurality of arms 42 (Fig. 3) each adapted to support a collector 44 for blanks. Conveniently the collectors are detachably secured to the arms 42 so that they may be removed if desired to permit of the substitution of other collectors therefor. As shown, each collector comprises a member 46 which is approximately of the shape of the article that the machine is designed to operate upon. Pivoted as at 48 upon the sides of the member 46 are two blank retaining members 50 (Figs. 4 and 5) having downwardly extending arms 52 with inturned blank supporting portions 54 constructed to present beveled ends 56 as disclosed especially in Figs. 1 and 4 of the drawings, and the operation of which will be pointed out later in the specification. For holding the blank supporting portions 54 in supporting position there is provided a spring 58 secured to pins 60 on opposite end portions of the retainers 50 below the pivots 48. It is obvious that the blank supporting ends 54 may be moved away from each other against the tension of the spring 58 to admit a blank into the lower end of the collector and that normally the portions 54 will be held in blank supporting position through the operation of the spring 58. Conveniently a detachable magazine 64 (Fig. 1) is adapted to be mounted upon each collector member 46 as an extension thereof to receive the blanks and is freely detachable so that it can be removed when filled and an empty one substituted therefor. This magazine may be held in place through the operation of spring clips (not shown) or by any other well known clamping means.

In the illustrated machine the table 10 serves not only as a feeding means or carrier for introducing blanks into the machine but also as the means for forcing the blanks upwardly into the collectors and magazines after the blanks have been calipered to determine their proper distribution. As shown, pockets 70 (Fig. 3) are provided on the table or carrier 10 into which the blanks B may be introduced at several stations along the periphery of the table, the pockets being of a shape to accommodate the particular blanks for which the machine is designed. Pivoted at 72 adjacent each pocket is a kicker 74 adapted to eject the blank from the pocket at a predetermined point in the rotation of the carrier. While the pockets are in blank receiving positions the kickers are held inoperative by reason of the

engagement of an elbow portion 76 of each kicker with a circular ledge 78 securely attached to the frame of the machine, as, for instance, at the ends of the arms 42 of the bracket 40. For operating the kicker when the latter arrives opposite a space or open portion in the ledge, there is attached to each kicker a spring 80 attached at one end to the carrier and at its other end to the kicker beyond the pivot point thereof, as shown in Fig. 3 of the drawings. It will be clear that when the pocket and the kicker come opposite the space or opening in the ledge 78, the kicker will be operated by the spring to eject the blank from the pocket as illustrated in Fig. 3 opposite station C. In the continued rotation of the carrier the elbow of the kicker again engages the ledge 78 and is repositioned with the spring 80 under tension. It will be understood that each pocket 70 comes in turn to station C in the rotation of the carrier and that each blank is ejected at this point into position above an ejector 84 located with its head portion even with or slightly below the plane of the upper surface of the table. There is an ejector 84 associated with each one of a series of pockets of an inner conveyor portion of the table now to be described.

As before stated the table or carrier 10 operates to introduce the blanks into the machine and also as a discharging means for the blanks. From one viewpoint then the member 10 comprises two conveyors concentrically arranged, of which the outer conveyor, as above described, is characterized by pockets 70 for receiving the blanks introduced by the operator. At station C the blanks are moved from the outer conveyor to the inner conveyor through the operation of the kickers 74, each blank being positioned over an ejector 84 and in a space between elevator members 86 distributed at regular intervals on the table 10, and serving to form certain of the walls of pockets in the inner conveyor. Other walls of the inner conveyor are formed by the ledge 78 already described and a second ledge 90 integral with or securely attached to the table 10. It is the wall or ledge 90 which positions the blank and holds it against the thrust of the kicker 74 when the latter moves the blank from the outer to the inner conveyor at the station C. Mounted in the inner conveyor portion of the table 10 is a plurality of members 84 referred to above as ejectors. As shown, each ejector comprises a shaft portion, slideable vertically in a bearing 94 (Fig. 1) secured to or integral with the table 10, and a link 96 pivoted to the shaft at 98 and normally held at an angle to the shaft through the operation of a spring 100, the link and the shaft forming a toggle, as will be herein-

after explained. For holding the shaft and therefore the ejector 84 in adjusted position there is provided a friction means comprising a hollow cylinder 104 (Figs. 1 and 5) 2) having a closed end to engage with a flat surface in a slot or groove 106 in the side of the shank of the ejector, a spring 108 serving to hold the cylinder pressed yieldingly against the said flat surface. 10 For holding the spring in position and for adjustably tensioning the same there is provided a cap piece 110 which is screwed in to the outer end of the cylindrical opening in the bearing 94 which receives the cylinder 15 104. Extending laterally from the lower end of the shank of the ejector is a pin which may be integral with the pivot 98 and which carries a roll 114 adapted to enter the flared opening 116 of the cam 20 track 120, (Fig. 2), the purpose being to position all of the ejectors successively and initially at the same height or position with respect to the upper surface of the inner conveyor portion of the table 10. 25 Conveniently the ejectors above described serve also as parts of a caliper means for the blanks in a manner that will now be described. Referring to Fig. 1 of the drawings it will be observed that the bracket 30 40 is provided with a bearing 126 for a relatively short shaft 128 having at one end a bevel gear 130 arranged constantly in mesh with a large bevel gear 132 secured to the journal 12 of the table 10 so as to move 35 with the latter. Mounted upon the outer end of the shaft 128 is a wheel 136 having pins or studs 138 arranged radially therein, all of the pins or studs being of equal length. In the illustrative construction 40 there are four pins 138 so spaced upon the wheel 136 and so operated from the shaft 128 and the gear above described that one of the pins comes into caliper relation with the upper end of each one of the ejector 45 members 84 during rotation of the table 10. It will be understood that if a relatively thick blank is positioned upon the upper end of an ejector 84 at station D, the caliper operation at station S (Fig. 3) will result 50 in forcing the ejector downwardly a greater distance than if a relatively thin blank were thus interposed between one of the pins and an ejector member 84. Since, as above described, all of the ejectors 84 55 have the same vertical position when they arrive at station S, the result of the caliper operation is to position the ejectors at different heights in their bearings in accordance with the differences in the thicknesses of the blanks. As a result of the caliper operations the ejectors are set to discharge the blanks at the proper discharge stations; so that all blanks of a given thickness may be deposited in one magazine 60 and all blanks of another thickness in an

other magazine, and so on. In other words, the caliper means controls the discharge of the blanks during the continued movement of the inner conveyor.

For operating the ejectors 84 there is provided, in the illustrative construction, a plurality of toggle operating members disclosed as posts 142 (Figs. 1, 4 and 5) mounted yieldingly for vertical movement in the frame member 20. As shown, each post 142 is 70 slidable vertically in a sleeve 144 screw threaded for adjustment in an opening in the lower portion or bottom 146 of the frame member 20, a spring 148 being arranged to surround the sleeve 144 and the post 142 75 to hold the latter yieldingly in its uppermost position which is determined through the presence of lock nuts 150 on the lower end of the post. Projecting from the sleeve 144 at the lower end thereof and into a slot or 80 groove in the post 142 is a pin 154 which operates to prevent rotation of the post 142 while permitting vertical movement of the latter within the limits fixed by the nuts 150 and the upper end of the sleeve 144. In 85 order that the sleeve 144 may be adjusted vertically and secured in adjusted position, and thus provide additional adjustment in a vertical direction for the post 142, there is provided an extension 156 at the lower end 90 of the said sleeve which is adapted to receive the set screw 158, the upper end of which threads into the base portion 146 of the frame 95 20 and serves to hold the sleeve 144 in adjusted position. As illustrated, the upper end of the post 142 is provided with a head 162 having a transverse ledge or abutment 164, the vertical face of which is positioned radially with respect to the center of rotation of the table 10 and thus in a position to be evenly contacted with by the lower beveled surface 168 on the end of the link 96. It will be clear that as the said surface 100 168 is initially presented to the abutment or edge 164 it is practically a vertical surface 110 (see Fig. 5) on the end of the link so that the ledge operates as a stop for the lower end of the toggle link. Hence as the toggle as a whole continues to move to the right in Fig. 5, the said toggle will be straightened 115 as indicated in Fig. 4, thus lifting the ejector 84 whereby it operates as an ejector to lift the blank away from the surface of the conveyor and toward the collector 44. Following this operation the blank is lifted into the 120 collector and magazine by means which will be hereinafter described. As the table 10 continues in motion the bevel surface 168, which is inclined at a considerable angle to the horizontal when the toggle is straightened, serves to force the post 142 downwardly against the tension of the spring 148, thereby permitting the toggle to pass on 125 without injury to either the post or the toggle. As an additional precaution to this end, 130

the toggle link 96 may yield beyond the straightened position of the toggle and against the pressure of the spring 100 by which the link is returned to its initial position with the toggle in broken position.

In order that the ejectors may be operated to eject the blanks when opposite the proper collector or magazine 44 in each case, the posts 142 are set progressively at different heights with respect to the collectors directly above them. For example, in the illustrative construction, the post 142 below the first collector 44 at station E (Fig. 3) is set the lowest of all the posts so that it can be contacted with by the lower end of that ejector toggle which has been depressed to the greatest extent during the caliper operation. In other words, the thickest blank of the range of blanks for which the machine has been set, will be ejected into the collector 44 and magazine at station E. At station F the post 142 will be slightly higher and the posts following will be progressively higher in a series extending around as far as the last collector at station J, where the thinnest blank will be ejected upwardly toward the collector 44 and magazine at this station. It is obvious that the posts 142 may be adjusted vertically for the purpose of changing the range of thicknesses of the blanks which the machine will handle from the thinnest to the thickest blank. On the other hand, only the posts 142 intermediate between the first and last posts may be adjusted so as to change the thicknesses for the intermediate ejectors. Furthermore, certain of the posts may be so adjusted as to be out of the range of operation of all of the ejectors, in which case blanks will be deposited in certain of the collectors 44 and magazines and not in all of them. It should be pointed out that the springs 148 of the toggle operating posts 142 serve the purpose also of an equalizing means, whereby the ejector which is the most depressed at the caliper operation, because it carries the thickest blank, is operated to elevate its associated blank to the same height, judging from the upper surface thereof, as that attained by the blanks on all the other ejectors. In other words, the springs 148 automatically condition the ejectors and their operating posts 142 so that allowance is made for differences in the thicknesses of blanks and in the position of the ejectors following the caliper operations. The toggles of the ejectors can be straightened without danger of damage to the blanks because of the presence of the springs 148.

It will be understood from the foregoing description that the ejectors 84 lift the blanks away from the inside conveyor and toward the collectors and magazines arranged above the conveyor, other means being preferably provided for elevating the blank and forcing it into the lower end of

the collector 44. As shown, these elevators comprise blocks 86 integral with or securely attached to the floor of the inner conveyor and having each a bevel or inclined surface 180 (Figs. 2, 6 and 7) that serves as a cam or wedge to lift the blank and force it into the collector. When the ejector 84 is operated to lift the blank through the straightening of the toggle it carries the latter to such a height that further movement of the blank in the direction of travel of the carrier is prevented because of the contact of the blank with the wall 190 of the selected collector 44 (Fig. 6). It will be obvious that as the carrier 10, together with the ejector 84 and elevator 86, continues to move while the blank is held from movement by the means described, that the blank will be elevated through the operation of elevator surface 180 on the block 86, the collector 44 being slotted as shown at 194 to permit the elevator to pass through in the direction of movement of the carrier 10. It will be understood that the elevator block 86 is of such a height as to force the blank up into the collector 44, during which operation the retaining members 52 are forced apart by contact of the blank with the beveled surfaces 56 on said members so that the blank is finally positioned above the supporting ends 54 of the retaining members 52, as indicated in Figs. 1 and 7 of the drawings.

In the operation of the machine blanks are placed by the operator in the pockets 70 of the continuously moving outer conveyor at various stations along the periphery of the latter. As each blank reaches station C it is operated upon by the kicker associated with each pocket 70 and moved into a pocket on the inner conveyor where it is located above an ejector 84 in the floor of the pocket. Between station D and station S, all of the ejectors are raised to the same height above the level of the carrier surface through the operation of the cam track 120. At station S the caliper operation takes place, during continued movement of the carrier or conveyor, whereby the ejectors 84 are depressed various distances in accordance with differences in the calipered thicknesses of the succeeding blanks of the continuous procession of blanks. Subsequently each ejector 84 is operated upon by one of the series of posts 142 to eject the blank into the collector for blanks of that given thickness. As the operation of the machine proceeds, the blanks are finally forced upwardly into magazines 64 above the collectors 44, the arrangement being such that the magazines may be easily removed when filled to permit of the substitution of empty magazines therefor. It will be clear that the blanks are automatically calipered as to thickness and discharged into the proper collectors or magazines without attention on

the part of the operator who is thus enabled to confine his efforts to keeping the pockets 70 filled with blanks and to the replacement of the magazines as the latter become filled.

5 Having thus described the invention, what is claimed as new and desired to be secured by Letters Patent of the United States is:—

1. In a machine of the character described, a continuously rotatable carrier having a 75 plurality of pockets in which blanks may be placed, a plurality of magazines with respect to which the pockets are successively related, and means controlled by a selected dimension of the blanks for ejecting each blank, during continued movement of the carrier, into the proper magazines so that the blanks are segregated in accordance with variations in the given dimension.

2. In a machine of the character described, 80 a carrier movable in a horizontal plane and having a plurality of pockets in which blanks may be placed, means for imparting continuous movement to the carrier, a plurality of magazines with respect to which the 85 pockets are successively related, and means movable with the carrier and also vertically toward and from the magazines and controlled by a selected dimension of the blanks for operating on the blanks to insure the discharge of the blanks into the proper magazines in accordance with predetermined 90 differences in the given dimension.

3. In a machine of the character described, 95 a movable member having a plurality of pockets in which blanks may be placed, each pocket having a movable bottom upon which the blank rests during movement of said member, and means controlled by a selected dimension of the blanks for causing operation of the movable bottoms of the pockets and thus insuring the discharge of the blanks at the proper stations for blanks of different 100 dimensions.

4. In a machine of the character described, 105 a movable carrier having a plurality of pockets in which blanks may be placed, and a plurality of ejector mechanisms movable with the carrier and controlled by a selected dimension of the blanks to effect discharge of the blanks from such pockets at a plurality of stations.

5. In a machine of the character described, a continuously movable carrier having a plurality of pockets in which blanks may be placed, and a plurality of ejectors controlled by the thickness of the blanks for operating on each blank to eject it from the pocket during continued movement of the carrier and at the proper discharge position for each blank.

6. In a machine of the character described, a continuously movable carrier having a plurality of pockets in which blanks may be placed, a plurality of magazines, and a plurality of ejectors controlled by

the thickness of the blanks for moving the blanks from the pockets toward the magazines during continued movement of the carrier.

7. In a machine of the character described, 70 a movable table for supporting blanks, means for caliperizing the blanks as they are successively presented to said means by the table, and magazines for the blanks, the table being provided with means movable therewith to project the blanks into the magazines in accordance with the determinations of the caliperizing means.

8. In a machine of the character described, 75 a member movable continuously in the same direction and having supporting surfaces for blanks, caliperizing means arranged to co-operate with the supporting surfaces for successively caliperizing the blanks as they are presented to said means, and magazines for the blanks, the said continuously moving member being constructed to deposit the blanks in the magazines in accordance with the determinations of the 80 caliperizing means.

9. In a machine of the character described, 85 caliperizing means for blanks, a member movable continuously and in the same direction for presenting the blanks to the caliperizing means, the said caliperizing means operating upon the continuously moving blanks, and magazines located above the continuously movable member for receiving blanks from the latter.

10. In a machine of the character described, 90 a carrier for blanks, a plurality of ejectors movable with the carrier, a member arranged to co-operate with each of the ejectors in turn to caliper the blank associated with each ejector, and means operative to remove the blanks from the carrier.

11. In a machine of the class described, a carrier having a plurality of pockets for receiving blanks, an ejector associated with each pocket to eject the blank therefrom, 100 means co-operating with the ejectors for caliperizing the blanks, a plurality of magazines, and means on the carrier co-operating with the magazines for depositing the blanks in the latter in accordance with the 105 determinations of the caliperizing means.

12. In a machine of the character described, 110 a continuously moving carrier for a plurality of blanks, ejectors movable with the carrier, and a plurality of magazines arranged to co-operate one with each ejector in removing the blanks from the carrier during continued movement of the latter.

13. In a machine of the character described, 115 a carrier for blanks, a plurality of magazines, ejectors movable with the carrier, and a caliperizing means for controlling the ejectors so that the latter co-operate one with each magazine to eject blanks from the carrier into the appropriate magazine.

14. In a machine of the character described, a carrier movable with a continuous movement in one direction, a plurality of magazines above the carrier for receiving blanks therefrom, a plurality of ejectors, and means for controlling the ejectors so that the latter will co-operate each with its respective magazine to deposit blanks in the latter.
15. In a machine of the character described, a carrier for blanks, magazines located in spaced relation along one side of the carrier, ejectors movable with the carrier for co-operating with the magazines to eject blanks into the latter, and a plurality of stationary members for controlling the ejectors.
16. In a machine of the character described, a carrier for blanks, a plurality of magazines above the carrier, and means on the carrier for selecting blanks in accordance with variations in a given dimension of the blanks and for ejecting the blanks into the proper magazines.
17. In a machine of the character described, a carrier for blanks, a plurality of magazines for receiving the blanks, a plurality of ejectors mounted to move with the carrier, and a member for co-operating with each ejector to caliper the blanks and to adjust the ejectors so that they will co-operate with the proper magazine to insure the deposit of the blanks in the latter.
18. In a machine of the character described, a carrier for blanks, a plurality of ejectors mounted to move with the carrier, means for positioning the ejectors in accordance with the thicknesses of the various blanks associated with ejectors, a plurality of magazines, and stationary members for causing the ejectors to deliver the blanks to the corresponding magazines.
19. In a machine of the character described, a carrier for blanks, a plurality of ejectors movable with the carrier, means for positioning each ejector in accordance with the thickness of the blank to be ejected thereby, and means for operating the ejectors at the proper discharge positions.
20. In a machine of the character described, a carrier having a plurality of pockets to receive blanks, caliper means for testing the thickness of each blank in the said pockets, the said means comprising an ejector, a plurality of magazines above the carrier, and means for causing the operation of the ejectors as they reach the proper magazines in accordance with the determinations of the caliper means.
21. In a machine of the character described, a carrier for blanks, a plurality of ejectors movable with the carrier, a plurality of magazines above the carrier, said ejectors comprising each a toggle mechanism, and a stationary member opposite each magazine for causing the operation of the toggle mechanism of the proper ejector as it comes into operative relation to the magazine in which the blank is to be deposited.
22. In a machine of the character described, a carrier having a plurality of pockets for blanks, a plurality of ejectors one for each pocket, a plurality of magazines, means for operating the ejectors to move the blanks from the pockets, and means associated with the carrier and operative to elevate the blank ejected from the pockets and deposit them in the proper magazine.
23. In a machine of the character described, a carrier for a plurality of blanks, a plurality of ejectors for moving the blanks upwardly from the carrier, said ejectors comprising each a toggle mechanism, a plurality of magazines, and stationary members of different heights located below the magazines and operative to straighten the toggle mechanisms to cause distribution of the blanks to the various magazines through the operation of the ejectors.
24. In a machine of the character described, a carrier for blanks, a plurality of ejectors movable with the carrier, a plurality of magazines above the carrier, means for operating the ejectors to lift the blanks toward the magazines, and elevators movable with the carrier to force the blanks into the magazines.
25. In a machine of the character described, a carrier for blanks, a plurality of magazines above the carrier, means for caliper the blanks, and elevators movable with the carrier for depositing blanks in the magazines in accordance with the determinations of the caliper means.
26. In a machine of the character described, a carrier for blanks, a plurality of ejectors movable with the carrier, means located above the carrier for co-operating with each ejector to caliper the blank associated with that ejector, the arrangement being such that the ejector is positioned in accordance with the thickness of the blank, a plurality of magazines, and stationary members located at different heights below the magazines and operative to force the ejectors upwardly toward the magazines so that the latter receive the blanks in accordance with the determinations of the caliper means.
27. In a machine of the class described, a carrier for blanks, a plurality of ejectors movable with the carrier, a member for co-operating with each ejector to move the latter downwardly a distance corresponding to the thickness of blanks located between the member and the ejector, and a plurality of members of different heights for operating on the ejectors to cause the latter to discharge the blanks at various stations in accordance with the determinations of the caliper means.

28. In a machine of the class described, a circular carrier having a plurality of pockets near its periphery into which the operator may place blanks, a plurality of magazines a second set of pockets on the carrier arranged to move below the magazines, means automatically operative to shift the blanks from the first set of pockets to the second, means for caliper the blanks in the pockets, said means comprising ejectors positioned in accordance with the thickness of the blank in each given pocket, said ejectors comprising each a toggle mechanism, and stationary members for straightening the 10 ejectors, said means comprising ejectors positioned in accordance with the thickness of the blank in each given pocket, said ejectors comprising each a toggle mechanism, and stationary members for straightening the 15 toggle mechanisms and thus operating the ejectors to discharge the blanks into magazines at stations decided by the determinations of the caliper means.
29. In a machine of the character described, a carrier for blanks, a plurality of ejectors associated with the carrier each comprising a toggle mechanism, means for positioning each ejector in accordance with the thickness of the blank associated therewith, 20 and stationary members operative selectively to straighten the toggle mechanisms of the ejectors to cause discharge of the blanks at the proper stations.
30. In a machine of the character described, a carrier having pockets for receiving blanks, a plurality of ejectors located in the pockets, means for positioning the ejectors in the pockets in accordance with the thickness of the blank over each ejector, 35 and means for actuating the ejectors at various discharge stations to distribute the blanks in accordance with the variations in thicknesses of the same.
31. In a machine of the character described, a carrier for blanks, means movable with the carrier for ejecting the blanks from the carrier, and a controller set in accordance with the thickness of each blank for ensuring the ejection of the blank at the 40 proper discharge station.
32. In a machine of the character described, a carrier for blanks, means movable with the carrier for discharging the blanks from the carrier at predetermined stations, a controller arranged to be set in accordance 45 with the thickness of each blank associated therewith and operative to ensure actuation of the discharging means, and means for positioning the controllers initially in the same relation to the carrier.
33. In a machine of the character described, a conveyor having pockets therein in which blanks may be placed, a second conveyor concentric with respect to the first mentioned conveyor, means for transferring blanks from the first to the second conveyor, and means associated with the second conveyor for caliper the blanks and for discharging them from the conveyor at stations 50 in accordance with the determinations of the caliper operations.
34. In a machine of the character described, a conveyor having means for carrying blanks in spaced relation with respect to each other, a second conveyor concentric with respect to the first and having means for carrying blanks in spaced relation, means for transferring blanks from the first to the second conveyor, caliper means for the blanks, and means for discharging blanks 55 from the second conveyor at stations determined with reference to the operations of the caliper means.
35. In a machine of the character described, a rotary conveyor having pockets for receiving blanks, a second conveyor concentric with the first mentioned conveyor and arranged to receive blanks therefrom, a plurality of magazines, and means associated with the second conveyor for caliper the blanks and for discharging them into the magazines in accordance with the determinations of the caliper operations.
36. In a machine of the character described, a conveyor having pockets for receiving blanks, a second conveyor concentric with the first and adapted to receive blanks therefrom, means for moving blanks from the first to the second conveyor, a plurality of magazines, means co-operating with the second conveyor to caliper the blanks and to discharge them into the magazines in accordance with the determinations of the caliper means.
37. In a machine of the class described, a rotary conveyor for receiving blanks to introduce them into the machine, a second conveyor concentric with the first and adapted to receive blanks therefrom, means for transferring the blanks from the first to the second conveyor, a plurality of magazines located above the second conveyor, and means for caliper the blanks as they are carried along by the second conveyor, said second conveyor having portions operative to elevate the blanks into the magazines in accordance with the determinations of the caliper operations.
38. In a machine of the character described, a carrier for receiving blanks, caliper means associated with the carrier and operative to caliper the blanks as they are presented in a continuous succession comprising axially movable plunger members adjustable in a caliper operation in accordance with the various thicknesses of the blanks presented to the caliper means, and means comprising a plurality of members progressively stepped in a series for operating on the plungers selectively in accordance with the adjusted positions of the latter effected during the caliper operations whereby the blanks are discharged.

- from the carrier in accordance with the determinations of the caliper means.
39. In a machine of the character described, a carrier for blanks, caliper means comprising a plurality of plungers for operating on the blanks as they are presented by the carrier, the said plungers being adjusted in position in accordance with the thicknesses of the successive blanks calipered, a plurality of magazines above the carrier, means for operating on the plungers to cause them to move the blanks toward the magazines selectively in accordance with the determinations of the caliper operations, and means on the carrier for completing the operation of forcing the blanks upwardly into the magazines.
40. In a machine of the character described, a carrier for blanks, means for caliper the blanks as they are presented in endless succession on the carrier, a plurality of members for ejecting the blanks from the carrier controlled by the caliper means so that they become operative at predetermined stations in the turning movement of the carrier, toggle mechanism connected with each of said members, and stationary means for operating the toggles at the different discharge stations.
41. In a machine of the character described, a carrier for blanks continuously rotatable to carry the blanks into the machine, continuously rotating caliper means timed to operate upon each blank in turn in the continuous succession of blanks, and means controlled by the caliper means for ejecting the blanks at discharge stations in accordance with the determinations of the caliper means.
42. In a machine of the character described, a carrier for blanks movable continuously in a given direction, means for caliper the blanks as they are presented by the carrier comprising plungers slidably mounted in the carrier, a plurality of magazines above the carrier, a plurality of stationary members mounted in line with the magazines and arranged to operate on the plungers in an order determined by the cali-

pering operations to cause the plunger to lift the blanks each toward its proper magazine, and elevator blocks on the carrier for moving the blanks upwardly into the magazines.

43. In a machine of the character described, a carrier for blanks, means for caliper the blanks as they are presented by the carrier comprising movable parts of the carrier arranged to be positioned adjustably by the caliper means in accordance with the thickness of the blanks calipered, magazines above the carrier to receive the blanks, and means for operating the movable portions of the carrier in an order determined with reference to the caliper operations to select the blanks for their respective magazines, the said carrier having other portions fixedly secured thereto which operate to force the selected blanks into the magazines.

44. In a machine of the character described, a carrier for blanks, means for caliper the blanks as they are presented by the carrier, a plurality of magazines located closely adjacent to the carrier, and means controlled by the caliper means for moving the blanks so that they engage an inside wall of the selected magazine to be retained against further movement with the carrier, the carrier having cam blocks secured thereto for elevating the blanks after they have been thus engaged with the magazines selected in accordance with the determinations of the caliper means.

45. In a machine of the character described, a carrier for blanks, means for caliper the blanks as they are presented by the carrier, a plurality of magazines located closely adjacent to the carrier, and means controlled by the caliper means for moving the blanks so that they engage an inside wall of the selected magazine to be retained against further movement with the carrier, the carrier having portions which serve to elevate the blanks after they are thus retained against movement therewith.

In testimony whereof I have signed my name to this specification.

RALPH C. SIMMONS.
